MARTIN B. PARKER AND RICHARD W. RICHARDS, OF BLUE EARTH CITY,
MINNESOTA.

HAY AND STRAW BURNER.

SPECIFICATION forming part of Letters Patent No. 250,961, dated December 13, 1881.

Application filed October 5, 1881. (No model.)

To all whom it may concern:

Be it known that we, MARTIN B. PARKER and RICHARD W. RICHARDS, of Blue Earth City, in the county of Faribault and State of Minnesota, have invented certain new and useful Improvements in Hay and Straw Burners, of which the following is a specification.

Reference is to be had to the accompanying drawings, forming part of this specification, in which similar letters of reference indicate corresponding parts in all the figures.

Figure 1 is a sectional side elevation of our improvement. Fig. 2 is a sectional plan view of the same, taken through the line *x x*, Fig. 1.

15 The object of this invention is to provide suitable means for burning hay, straw, and other light fuel for cooking and heating purposes.

20 A represents the body of the burner, which may be made of cast, boiler, or sheet iron, or partly of cast-iron and partly of boiler or sheet iron.

25 B is a funnel or spout connected with the opening C in the burner for convenience in introducing the fuel. The funnel B may extend through a partition into a fuel-room, and is provided with a door, D, at its outer end.

30 The funnel B is provided with a sliding door, D', inserted through the outer end of the said funnel, and which serves the double purpose of pushing the fuel through the said funnel into the fire-chamber, and of preventing the funnel from becoming unduly heated; or the funnel B may be omitted and the fuel introduced through the opening C, in which case the said opening is provided with a door. The fuel, while being burned, is compressed between two grates, E F. The upper grate, E, is stationary, is placed a little distance below the

35 top of the burner, and is attached to the upper ends of rods G, the lower ends of which are attached to the bottom of the burner A. The rods G serve as guides to the grate F when moving up and down, and also keep the fuel away from the sides and ends of the burner, to form open spaces for the free escape of the smoke and gaseous products of combustion.

40 To the corners of the grate F are attached the ends of chains H. The forward chains H

50 pass over guide-pulleys I, and pass back beneath the top of the burner. The ends of all the chains H are attached to a shaft, J, revolving in bearings in the upper parts of the sides of the burner, so that the grate F will be raised and lowered by turning the shaft J. 55 The shaft J is turned by means of a crank, K, attached to its projecting end, and is held from being turned by the weight of the grate F by a pawl, L, which engages with a ratchet-wheel, M, attached to the said shaft. Air to support 60 combustion enters through openings N in the rear wall of the burner, and in the front door, O, of the said burner, which openings are regulated by slides P in the ordinary manner. Enough space can be left beneath the grate F 65 to receive the ashes from a day's burning; or the ashes may be received in a pan, Q, slid into the lower part of the burner; or the bottom of the burner can have an opening formed in it, closed by a slide and connected with a pipe 70 or spout leading into an ash-receiver in the cellar, and through which the ashes can be discharged when desired.

75 In the upper rear part of the burner, between the upper grate, E, and the top of the said burner, is secured a partition, R, to direct the products of combustion beneath the boiler-holes S. The partition R is made in two parts or sections, the forward part or section sliding upon the rear part, so that the main volume 80 of heat can be directed against any desired part of the top of the burner.

To the rear part of the top of the burner A is secured an oven, T, the walls of which are made double, so that the space U between the 85 said walls will serve as a flue to conduct the products of combustion to the smoke-pipe V. The space or flue U is connected with the interior of the burner A by an opening, W, within which is placed a guide-plate, X, to divide 90 the products of combustion and cause them to pass up upon both sides of the oven T. When the oven is in use a part of the products of combustion can be allowed to pass through an opening, Y, in the partition R, and 95 be guided to the opening W by a plate, Z. The plate Z, or both the plates Z X, can be movable, to adapt them to serve as dampers to regulate

late the draft. The ashes are prevented from passing through the opening W Y by wire-gauze screens *a*.

Having thus fully described our invention, 5 we claim as new and desire to secure by Letters Patent—

1. In a hay and straw burner, the combination, with the body A, of the stationary grate E, the supporting-rods G, the movable grate 10 F, the chains H, and the crank-shaft J, substantially as herein shown and described, whereby the fuel can be compressed while being burned, and a draft-space kept open all around the said fuel, as set forth.

15 2. In a hay and straw burner, the combination, with the body A, having opening W, the

partition R, having opening Y, and the double-walled oven T, of the plates X Z, substantially as herein shown and described, whereby the products of combustion are directed into and 20 distributed through the oven-flue, as set forth.

3. In a hay and straw burner, the combination, with the body A and the partition R, of the wire screens *a*, substantially as herein shown and described, whereby the ashes are 25 prevented from entering the flue of the double-walled oven, as set forth.
